AIR CONDITIONING SYSTEMS

Louis F. Mercatanti, Trenton, N.J., assignor to Fedders-
Quigan Corporation, Maspeth, N.Y.

Application September 9, 1957, Serial No. 682,887

1 Claim. (Cl. 98—39)

This invention relates to air conditioning systems.

In air conditioning systems it is desirable to appor-tion a minor volume of outside fresh air to the air that is being recirculated within the heated or cooled spaces of a building. This has long met with an objection from a safety point of view, in that in the event of a fire fresh outside air would be drawn into the building to feed the fire, at least until such time as the motor driven blowers were rendered inoperative. It is proposed in the present invention to obviate this hazard by supplying a heat responsive mechanism, which will respond in a positive manner to close the dampers which permit fresh air entry.

The invention will be more clearly understood by referring to the accompanying specification and drawings wherein:

Fig. 1 is a perspective view of an air conditioning unit with part of the casing removed to show the thermal damper control of the invention;

Fig. 2 is a vertical section thru Fig. 1;

Fig. 3 is a section on the line 3—3 of Fig. 2;

Fig. 4 is an exploded perspective view of the thermal damper control.

For exemplary purposes the invention is shown organized with a heating unit 10 having a casing 11, wherein are housed motor driven blowers 12, which draw air thru a port 13 low in the casing and an overlying filter 15 within the casing and then force the air thru a heating coil 14 and thence back into the room. The casing 11 is mounted adjacent a wall W which is pierced to provide an inlet port 16 for outside air. The casing 11 is provided with a registering port 16a, the opening of which is controlled by a damper 17 which is hinged, as indicated by the numeral 18, to the base structure 19 of the casing 11. The damper 17 may be controlled in any suitable manner; for example, by a manually operable bell crank 21 pivoted to the base structure 11 by a stud 22 and carrying a spring wire 23 leading to and affixed to the damper 17. A bracket 24, adjacent the damper 17 serves as a mounting means for a guide sheath 25 for the wire 23 and also as a support for the mechanism 20 of the invention.

It will be observed that the mechanism 20 is not mechanically associated with the operating members of the damper 17, being mounted as shown in Figs. 2 and 3 on the bracket 24 in spaced relation to such members. The mechanism 20 consists of externally threaded bushing 27, which is entered thru a suitable hole 28 in the bracket 24 and secured by a nut 38. A plunger 29 is slidably mounted in the bushing 27 and at one end car-

2

ries a compression spring 30, which is retained by a nut 31 and washer 32. The remaining end of the plunger 29 is formed with a hook terminal 33.

A stanchion in the form of a bolt 34 is secured to the bracket 24, adjacent to the bushing 27 by nuts 35, and the free end of the bolt is provided with a hook terminal 36. A link or fusible element 37 is pierced with spaced holes 39 to receive the terminals 33 and 36 of the plunger 29 and bolt 34, respectively to complete the assembly. It will be noted that the spring 30 may be suitably proportioned so that in this assembly it will be placed under full compression with the nut 31 being located immediately adjacent the inner face of the damper 17 and with the link 37 retaining the assembly in such a pre-set position.

The link 37 is formed of a low-melting bismuth alloy, which is fusible at temperatures around 150° F. Thus, in the event of a fire the hot air drawn from the floor into the unit 10 first passes the link 37, which in melting releases the spring pressed plunger 29 for a strong thrust on the damper 17 in the direction of closing of the damper, as shown in dot and dash lines of Fig. 2. Under normal conditions the elements of the mechanism 20 do not interfere with the opening or closing of the damper or the operating mechanism for performing this function.

It will be apparent that the mechanism 20 with slight modification may be installed in many of the existing air conditioning systems adjacent the outside air dampers 30 thereof. It is, therefore, not intended to limit the invention to the precise installation herein described, except as may be required by the scope of the following claim.

I claim:

35 In an air conditioning system including a casing having a fresh air inlet port, a damper within said casing, pivotal mounting means in said casing for mounting said damper for movement from a position covering said port, manual operating means connected to said damper for moving said damper to an open position uncovering said port, a 40 plunger, a bracket mounted in the casing and including a bushing for receiving said plunger for axial guided movement toward the body of said damper remote from said pivotal mounting means, a spring carried by said plunger and engaging said bracket, said spring being 45 adapted to urge said plunger into contact with said damper to retain said damper in closed position, said plunger extending thru said bushing and having a terminal remote from said damper formed with a hook portion, a stanchion carried in the casing in spaced relation to said 50 bracket, a fusible member having spaced openings therein engaging over the stanchion and the hook portion of the plunger respectively, said fusible member retaining said plunger in a withdrawn position relative said damper to permit unobstructive operation thereof during normal 55 conditions.
